METHOD OF AND MECHANISM FOR TREAT-
ING STEREO TYPE MATRICES

George M. Clark, Lynn, Mass.

Application May 20, 1931. Serial No. 538,757

8 Claims. (Cl. 210—66)

In the preparation of stereotype plates a flat paper matrix sheet containing from 12% to 15% of moisture is laid on the type surface of the forme and the forme, matrix sheet and a superposed matrix blanket are run through the nip between pressure matrix rollers, this causing the type to be deeply impressed in the matrix sheet. This sheet, after being suitably conditioned, is used to form a curved mold face against which molten metal is cast to form the stereotype plate. The impressing of the type in the matrix causes this sheet to warp and buckle and heretofore so far as I am aware no entirely satisfactory method or mechanism for accurately and quickly shaping and drying it has been developed. If the matrix does not lie over any areas firmly against the inner face of the mold chamber, the stereotype plate will print lightly or not at all at those areas. As the matrix dries, moreover, it shrinks and if the drying is not uniform this shrinkage is uneven which results in the lines of the type in the curved plate being non-parallel and often in portions of the lines being cut away when the edges of the plate are trimmed preparatory to assembly on the printing cylinders.

In accordance with the present invention the matrix is formed to the proper even curvature by subjecting it to centrifugal force while it is contained in a tube the inner wall of which is of the curvature desired for the outer face of the finished plate, and it is dried by a current of hot air which uniformly contacts with all the parts thereof.

For a more complete understanding of this invention reference may be had to the accompanying drawings in which

Figure 1 is a fragmentary view, partly in elevation and partly in vertical section, through the forming and drying machine.

Figures 2 and 3 are horizontal sections on lines 2—2 and 3—3, respectively, of Figure 1, Figure 2 also showing a wiring diagram for the heating units.

Figure 4 is a perspective partly broken away, showing the rotating tube for carrying the matrix, together with related parts.

Figure 5 is a fragmentary sectional detail to a larger scale showing the matrix and tube.

Referring to the drawings, at 1 is indicated a base formed with a central opening 2 therethrough. Projecting upwardly from this base are three posts indicated generally at 3, which support at their upper ends an annular bottom wall 4 of a cylindrical casing 5. Each post 3 comprises aligned tubular members 10 and 11 sepa-

rated by a perforated arm portion 12 of a central spider 13, these parts being held together by a bolt 14 having its head 15 seated in a socket 16 in the lower face of the base 1 and engaged at its upper end in a threaded opening 17 in a boss 18 projecting downwardly from the bottom wall 4. The spider 13 is provided with a plurality of downwardly and inwardly turned arm portions 20 from and on the under side of which is hung by bolts 21 an electric motor 22, this motor being of an outside diameter sufficiently small to be passed through the opening 2 of the base in order to facilitate its assembly or detachment from the remainder of the mechanism. This motor is provided with a vertical armature shaft 24 which may be coupled through the coupling collars 25 and 26 with their interposed resilient disk to a vertical shaft 28. The collar 25 is carried by the armature shaft and the collar 26 by the shaft 28. This vertical shaft extends through a bearing member 30 which is provided with ball bearings 31 at its upper end and ball bearings 32 at its lower end. The shaft 28 is provided with a shouldered portion 33 which rests on the inner race of the ball bearing 32 and this ball bearing is supported from the lower end of the bearing member 30 as by the ring 35 bolted thereto. This lower bearing, therefore, acts as a thrust bearing to take the weight of the shaft 28 and the parts supported thereby. The bearing 30 is mounted to float yieldingly so that it can adapt itself to the forces transmitted to it as the shaft 28 and the parts carried thereby are rotated at various speeds, including the critical speed above which the shaft 28 and its supported parts rotate about their gravity axis rather than about their geometrical axis. To this end the bearing 30 is yieldingly supported by the spider 13. This spider is provided with a receptacle portion 40 having a centrally perforated lower wall 41 on which rests a washer of rubber or similar yieldable material as 42. On the upper face of this washer rests a flange 44 projecting outwardly from the central hub portion 45 of the bearing 30 and resting on this flange is another resilient washer 48 similar to the washer 42. These washers and the flange therebetween are retained in position by a ring member 50 fixed on the upper edge of the receptacle portion 40 and projecting inwardly over the washer 48. The flange portion 44 is of somewhat less diameter than the inner face of the receptacle 40 so that the bearing member is permitted a considerable yielding lateral play to adapt itself to the rotational forces imparted to the shaft 28 of the motor 22. The spider 13 is

provided with strengthening flanges 52 and 53 which serve to reinforce the various parts without adding materially to the weight of the spider. It will be seen that the motor and the shaft 28 are supported at three points spaced angularly by the posts 3.

The bottom wall member 4 is provided with an upturned marginal flange 60 which surrounds the lower end of a cylindrical side wall 61. As 10 shown this wall is formed by an annular channel-shaped lower member 62 having its flanges upwardly directed and an annular top member 64 having downwardly directed annular flanges 65, 66 and 67 united by vertical curved plates 63 and 15 68 fixed to the outer face of the lower member 62 and to the inner faces of the flanges 64 and 66 of the upper member and which form spaced walls between which is placed heat insulating packing of asbestos or the like as at 69. The 20 upper wall 64 is provided with a grooved rim portion 70 against which may be seated a removable cover member 71. This cover member is provided with a dome shaped upper wall 72 having spaced lugs 73 extending downwardly therefrom to which may be fixed a disk shaped plate 74 which holds heat insulating packing 75 in position between this plate and the portion 72. A bell crank lever 77 fulcrumed as at 78 and pivoted to suitable lugs on the cover member at 79 may 25 be used to close or open the cover member. Inwardly of the side wall plate 68 the bottom wall member 4 supports an annular plate 80 of heat insulating material through the central opening of which the shaft 28 projects and on the upper 30 face of this plate is supported a metal ring 81 which forms one portion of a cylindrical cage or frame. This cage is provided with an upper metal ring 82, these rings being spaced apart by the tubular spacers 83 through which are extended the tie rods 84. This cage or frame provides means for supporting the electric heating units as 90 which may be attached at their ends to the rings 81 and 82. Within this frame, which carries the electric heating units, the shaft 28 has 40 fixed thereto a light weight tubular receptacle 100 made of aluminum or the like shown detached in Figure 4. This receptacle is open at its upper end where it is provided with an outwardly turned flange 101. Its lower end is closed off by a disk member 105 having a marginal upwardly extending flange 106 to the outer face of which the tube 100 is suitably secured. Centrally the portion 105 has an upwardly extending hub portion 107 which may be provided with a tapered bore 50 108 to receive the upper tapered extremity of the shaft 28. These may be brought into tight engagement as by means of a screw 109 and washer 109a, the washer resting on the top of the hub 107 and the screw being threaded into the upper 55 end of the shaft 28. The flange 106 and the lower end of the tube 100 are provided with mating openings 110 through which air may be passed, and in order to create a current of air through these openings, a fan 111 is provided.

60 This fan comprises an annular plate 112, the margin of which is supported on the top of the flange 106, and has a central upwardly extending flange portion 113 spaced from the hub 108 to form an air passage therebetween. From the 65 lower face of the disk 111 extend fan blades 115 which project toward the upper face of the member 105. This fan rests by its own weight in the lower portion of the receptacle and in order that it may be rotated as the receptacle is rotated, 70 means such as screws 116 may be threaded up

through the base member 105 in position to contact with any of the blades 115 so as to carry the fan around as the tube is being rotated. Rotation of the tube thus causes the fan to take air in from the inside of the tubular receptacle, force it 80 cut through the openings 110 into the space between the receptacle and the inner wall of the insulated casing in which are positioned the heating elements, the air thus being heated and being passed upwardly within the casing flange 67 and 85 down through from the top of the tubular receptacle. There is thus created by the rotation of this receptacle a strong current of air which passes upwardly about the heating units outside of the tubular receptacle and then down there- 90 within.

The tubular receptacle 100 is designed to receive the matrix which, after the type has been impressed therein, is curved up sufficiently so that it can be placed in the tubular receptacle as 95 shown at 120 in Figures 4 and 5. This matrix is then in a damp somewhat soft condition so that when the receptacle is spun at a high rate of speed centrifugal force causes its outer face to press firmly against the inner smooth wall of the tube 100 thus to smooth out buckles, puckers or other 100 uneven portions resulting from the buckling or other distortion of the material arising through the impressing of the type thereinto. The tube 100 is provided at suitable intervals with small 105 perforations 125 therethrough through which water from the moist matrix may be expelled. These perforations are of sufficiently small diameter so that they do not form marks on the outer face of the matrix due to the pressure of 110 the matrix thereon under centrifugal force. They should not exceed about $\frac{1}{16}$ of an inch in diameter. As the outer face of the matrix is broken up more or less by the type impressions, channels are thus formed in the outer face which permit 115 the water to pass over substantial areas to these perforations 25, and by permitting the escape of water in this manner the amount which it is necessary to remove by drying is reduced.

Where there are substantial matrix areas which 120 carry no type impressions and are not depressed, these representing areas over which no printing is to be effected, it may be found necessary to place strips of felt or the like as at 126 on the other faces to prevent these areas from being 125 drawn outwardly by centrifugal force into contact with the tube wall in which position they would permit the plate cast thereagainst to print. The use of these strips however, is usual practice in connection with the conditioning of 130 matrices.

The matrix having been placed in the tube and the cover 71 closed, the motor is then brought up to high speed rapidly, not only causing the matrix to be properly conformed to the wall of the tube 135 but also to cause it to be dried out so that it is reduced to firm condition. The matrix may fill substantially the entire circumference of the tube 100 or it may be curved to fit a portion only, such as one-half thereof, in which case two matrices 140 may be treated together, or the unfilled portion of the complete arc may be occupied by a dummy spacer which may be made of aluminum or other light material in order to better balance the rotating parts.

Where a tube of $7\frac{1}{4}$ " in internal diameter is employed this machine may reach a maximum speed of nearly 3500 revolutions per minute and the maximum air temperatures may be in the 150

neighborhood of 500° F. or even higher. As such heat if long continued would burn the matrix material, the entire treatment is made very short, it being found possible to shape and dry or "scorch" 5 the matrix in a minute or less. It is thus important that the motor be capable of quickly starting and stopping and operate at very high speed. It is also important in running at such high speeds that the rotating parts be accurately balanced as at the critical speed where the axis of rotation changes from the geometric axis to the gravity axis a considerable wabbling of the rotating parts may occur. The depending flange 67 of the outer casing acts with the top flange 101 10 of the rotary tubular receptacle as a safety device so that if the tubular receptacle is improperly loaded so that it is far from balanced, the flange 101 contacts with the flange 67, this contact acting as a brake to sufficiently reduce the speed of the 15 rotation so that it cannot rise above its critical speed and the noise occasioned by this rubbing calls attention of the operator to the fact that the tubular receptacle is improperly loaded. The motor may be stopped by electric braking control, as is well known in the electrical industry, or if 20 desired a mechanical brake may be employed for this purpose. As shown in Figure 1 the shaft coupling member 26 is formed as a brake drum about which is positioned a brake band 130, one 25 end of which may be fixed and the other engaged over a pin 131 in the lower end of an arm 132 carried by a brake shaft 133 having an actuating handle 134 at its upper end.

When desired the casing surrounding the rotating parts may be removed by merely removing bolts such as 135 which secure the ring 62 to the bottom wall 4, it being ordinarily sufficient to use a pair only of such bolts situated diametrically opposite to each other. At 140 is shown a switchboard secured at its lower end as by the screw 141 to the base member 1 and somewhat below its upper end as by a screw 142 to the flange 60. This switchboard may carry the control mechanism for the motor and also 45 control mechanism for the electric heating units. This may include a thermostat control for regulating within the desired limits the temperature of the air being circulated, a temperature responsive bulb element within the casing being shown at 145 on Figure 1 from which a tube 146 50 leads to a suitable electrical control device (not shown but well known in the art) on the switchboard 140. The case or frame which supports the heating elements also acts through its metal 55 parts as a heat balancing device tending to prevent rapid fluctuations of temperature, due for example to opening or closing the cover, these parts absorbing heat when the cover is closed and giving it off again to the air when the temperature of this air drops for any cause momentarily. It will be noted that the switchboard is 60 entirely separate from the casing so that the removal of this casing in no way disturbs the electrical wiring to the motor or the heating units.

In Figure 2 is shown diagrammatically one 65 arrangement of heating units by which three ranges of heat may be produced, low, high and moderate, designated by the corresponding letters on the control switch 150. At the low heat, two of the units alone are energized; at the moderate heat four are energized, and at the high heat all are energized. This particular control mechanism per se, however, forms no part of this invention, there being various hook-ups

which can be employed as desired to produce the desired graduations in temperature.

From the foregoing description of this invention and of an apparatus by which the desired treatment of the matrix may be carried out, it should be evident to those skilled in the art that various changes and modifications might be made without departing from the spirit or scope of this invention as defined by the appended claims.

I claim:

1. The method of conditioning a moist stereotype matrix, which comprises curving said matrix to substantially the desired contour, and while supporting substantially its entire surface against undesired outward movement, rotating said matrix about substantially its axis of curvature at high speed.

2. The method of conditioning a moist stereotype matrix, which comprises curving said matrix to substantially the desired contour, and while supporting substantially its entire surface against undesired outward movement, rotating said matrix about substantially its axis of curvature at high speed, and drying said matrix while 100 it is being rotated.

3. The method of conditioning a moist stereotype matrix, which comprises curving said matrix to substantially the desired contour, and while supporting substantially its entire surface 105 against undesired outward movement, rotating said matrix about substantially its axis of curvature at high speed, and passing a current of hot, dry air across the inner face of said matrix while it is being rotated.

4. A mechanism of the class described comprising a casing, a cylindrical tube mounted for rotation within said casing and within which a matrix in curved condition may be placed, said tube having one end open and the other closed, a shaft 110 fixed to said closed end by which said tube may be rotated, said tube having openings therethrough adjacent to said closed end, a fan member within said tube at said closed end and rotatable therewith and having blades positioned to 115 take air from within said tube and discharge said air through said openings, heating means in said casing outwardly of said tube, and means for rotating said shaft at high speed.

5. In a machine of the class described, an upright tubular member open at its upper end, a closure for the lower end of said member comprising a disk having a marginal upwardly extending flange engageable with the inner face of 120 said member and a central shaft receiving hub, 125 said member and flange having mating openings therethrough, a fan having a plate portion resting on the upper edge of said flange within said member and having downwardly extending blades, and means rotatable with said member for 130 engaging and imparting rotation to said fan.

6. A mechanism of the class described comprising a casing having an annular bottom wall, side walls and a top wall including a central removable cover, said side walls and top wall being supported on and detachably secured to said bottom wall, a base, posts rising from said base and fixed to said bottom wall, a motor fixed between said posts, a vertical shaft driven by said motor and extending up through the central opening in said 140 bottom wall, a receptacle carried by the upper end of said shaft within said casing, a switchboard fixed to said base and to said bottom wall and free from said side and top walls, whereby said side and top walls may be removed without dis- 145 150

turbine said switchboard, and control devices for said motor carried by said switchboard.

7. A mechanism of the class described comprising a casing having an annular bottom wall, 5 side walls and a top wall including a central removable cover, said side walls and top wall being supported on and detachably secured to said bottom wall, a base, posts rising from said base and fixed to said bottom wall, a motor fixed between said posts, a vertical shaft driven by 10 said motor and extending up through the central opening in said bottom wall, a receptacle carried by the upper end of said shaft within said casing, heating units supported by said bottom wall within said casing and outwardly of said receptacle, a switchboard fixed to 15 said base and to said bottom wall and free from

said side and top walls, whereby said side and top walls may be removed without disturbing said switchboard, and control devices for said motor and heating units carried by said switchboard.

8. A mechanism of the class described comprising 80 a cylindrical casing having heat insulating walls, a cylindrical tube rotatable within said casing and within which a matrix in curved condition may be placed, a cylindrical cage surrounding and spaced from said tube and within said 85 casing, said cage having end ring members, a plurality of electric heating units extending between and fixed to said end ring members, and means for controlling the supply of electrical 90 energy to said elements.
